UNITED STATES PATENT OFFICE.

JAMES F. FLAHERTY, OF PHILADELPHIA, PENNSYLVANIA, ASSIGNOR OF ONE-HALF TO HUGH J. FAGEN, OF PHILADELPHIA, PENNSYLVANIA.

CARBOY-INCLINATOR.

SPECIFICATION forming part of Letters Patent No. 772,461, dated October 18, 1904.

Application filed January 29, 1904. Serial No. 191,183. (No model.)

To all whom it may concern:

Be it known that I, JAMES F. FLAHERTY, a citizen of the United States, and a resident of Philadelphia, in the county of Philadelphia and State of Pennsylvania, have invented certain new and useful Improvements in Carboy-Inclinators, of which the following is a specification.

My invention relates to improvements in devices for inclining or tilting carboys or similar articles incasing liquids, and has for its object the production of simple and efficient means for manipulating the carboy to which it is attached for the purpose of pouring from it a portion or the whole of its contents.

A further object is to provide a device that can be instantly applied or removed without raising, handling, or operating the carboy in any way or causing damage to it and which can be readily adapted to suit various sizes.

In the drawings, Figure 1 is a plan view of my device attached to a carboy; Fig. 2, a side elevation of the same; Fig. 3, a front elevation, and Fig. 4 a side view, of the operating-cam.

Referring to the drawings, A represents a carboy or similar large vessel inclosed in a protective wooden casing except at its mouth and neck, which extend through and above the top of the said case.

In my device are one or more curved rockers 1, connected together by a cross-piece 2 and provided with appropriate braces 3, which come into contact with the back of the wooden casing and have next the casing one or more sharp-pointed spurs 4 to enter and engage therewith. Connected with the upper ends of these rockers are bars or straps 5, adapted to rest upon the top of the casing, arranged to avoid any interference with the projecting portion of the carboy, and having at their front end a slotted post 6, terminating in an enlarged head 7, adapted to be grasped by the hand of the operator, the said post acting as a hand-lever for the purpose of tipping the carboy.

Within the slotted post 6, near its lower end, is pivotally attached a spirally-grooved cam 8, the pintles of which rest and revolve in

guideons formed in the side walls of the said post. On one side the pintle is extended through beyond the outer line of the post, and suitable connections are made with one end of the hand-lever 9, which is bent to avoid the neck of the carboy and whose function it is to operate the said cam. A bent lever 10 also passes through the upper end of the slotted post 6 and is provided with a series of holes for adjusting to varying sizes of carboys. A bolt 11 engages with these holes, passing through the post, forming a pivotal bearing within it. This lever is bent downwardly at right angles to the upper portion and has a small reentrant angle at its extreme end terminating in a spur 12, adapted to enter into and engage with the wooden front of the case opposite to the rockers. Midway in the length of this lever and in the same plane with the cam is a forked projection 13, extending inwardly on both sides of the cam 8, and is further provided with a stud or bolt 14, which passes through the spiral groove in the cam, connecting the two members loosely but operatively together.

In operation my device is placed in position on an incased carboy, and the hand-lever moved so as to cause the cam to partly rotate in the direction which will shorten the radial distance between the groove and its axial center. This movement causes the post and parts to which it is attached and the bent lever 10 to be drawn together or toward each other, resulting in forcing the spurs to enter into the wood on opposite sides of the case, thus affording a substantial grip. The shape of the cam-groove is such that it will remain in whatever position the lever leaves it, thus effectually locking itself. Now by taking hold of the handle formed by the head of the post 7 and using it as a lever the carboy can be readily tilted over upon the rockers and on them as far as may be required. By reversing the action of the hand-lever 9 the spurs are freed from the carboy and the device can be removed or transferred at will.

It will be seen that this device affords a thoroughly efficient means for handling a carboy in discharging its contents, avoiding the

danger of spilling or splashing in pouring therefrom and the loss and possible damage consequent thereto, the carboy being placed at all times under easy control of the operator.

5 Having thus described my invention, what I claim, and desire to secure by Letters Patent, is—

1. In a carboy-inclinator, the combination of one or more rockers, provided with spurs; 10 a clamping-lever oppositely disposed to the rockers, and a connecting member attached to the rockers at one end and with the clamping-lever at the other, substantially as shown and described.

15 2. A carboy-inclinator consisting of one or more rockers, provided with spurs; a member connecting with the rockers at one end having a clamping-lever, also provided with spurs, pivoted at the other end; a spirally-grooved 20 cam controlling the said clamping-lever, and a hand-lever operating the said cam, all substantially as shown and described.

3. In a carboy-inclinator, the combination of one or more rockers, provided with spurs, 25 adapted to engage with one side of a carboy; a bifurcated strap or bar connected at its double extremities to the said rockers and having, at its single extremity, an adjustable clamping-lever, provided with spurs adapted to engage

30 with the opposite side of the carboy, and having at its upper end a series of holes for adjustment; an operating-lever post, integral with the said bifurcated bar; a cam adapted to convey motion to the said clamping-lever, and a handle for turning the said cam, all substantially as shown and described. 35

4. In a device of the class described, the combination of a rigid frame, having downwardly-extending outer surfaces corresponding to the arc of a circle; a member at right angles thereto 40 and integral therewith, provided, near its opposite end, with a slotted post; a lever working within the said post, adjustably attached thereto at one end, the other terminating in an inwardly-turned spur; a cam adapted to 45 operate the said lever, causing it to move inwardly or outwardly, and remain locked in such position; a hand-lever for operating the said cam and a tilting lever, integral with the said slotted lever, all substantially as shown 50 and described.

In testimony whereof I have affixed my signature in presence of two witnesses.

JAMES F. FLAHERTY.
